Primary Examiner — Patricia Ann Palasik*(74) Attorney, Agent, or Firm* — Locke Lord LLP(57) **CLAIM**

The ornamental design for a drill bit tip, as shown and described.

DESCRIPTION

FIG. 1 is a perspective view of a drill bit tip.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged detailed perspective view of FIG. 1. The broken lines in the drawings depict unclaimed environmental subject matter.
